UNITED STATES PATENT OFFICE.

WILLIAM J. BURROWS, OF ST. PAUL, MINNESOTA.

METHOD OF MAKING LEAD CAMES.

Application filed June 17, 1926. Serial No. 116,588.

This invention relates to the method of decorating and finishing lead cames wherein it is desired to provide a lead came of an artistic design.

5 The method includes the applying of forming different decorative surfaces on the cames in a simple and effective manner by changing the master patterns.

A further object of the invention resides 10 in finishing and forming cames in a manner so as to draw out the came body and at the same time impress into the surface thereof such decorative designs as to provide a very attractive and desirable came which is used 15 for leaded glass windows and the like. My invention is designed to carry out the method in an economical, simple and practical manner, permitting the formation of the cames with such a decorative facing over 20 the entire outer surface of the same as may be desired. The lead cames are of a soft nature and are readily receptive to impressing designs into the surface of the same, and my method is carried out in making the 25 cames in a manner so as to facilitate the accomplishing of the method without extra operation and expense.

These features, together with other objects and details of the carrying out of the 30 method will be more fully and clearly set forth in the specification and claims. To facilitate the clear understanding of the carrying out of my method I have chosen to illustrate in the drawings a simple machine designed to make the cames.

Figure 1 illustrates a front view of this machine.

Figure 2 is a plan view of the same.

Figure 3 is a side elevation of the same.

40 Figure 4 is a diagrammatic side view.

Figure 5 illustrates a portion of the came before it has been finished by my method.

Figure 6 illustrates a portion of the came as it would appear when finished by my 45 method.

In carrying out my method the lead came such as A illustrated in Figure 5 is in its ordinary drawn state as it appears after it comes from the extrusion machine, and the 50 came A illustrated in Figure 5 is designed with a center steel reinforcing member 10 which is placed into the opening designed to receive the flat bar-like steel member. This opening is formed in the came as the 55 same comes through the extrusion machine and the steel band is inserted within the

same just before the carrying out of my pressing method. The structure of this reinforced came is the subject matter of another and separate application.

In carrying out my method the came A which is made of soft or comparatively soft lead material is adapted to be passed into the forming wheels 12 and 13 carried on the shafts 14 and 15, respectively. The shafts 65 14 and 15 are supported in the side 16 of the forming machine B.

The machine B is provided with an operating pulley 17 which is adapted to drive the shaft 18, which in turn drives the gear 70 19, positioned on one side of the machine B. The gear 19 meshes with the gear 20 which operates the shaft 21 and drives the gear 22 on the opposite side of the machine to the gears 19 and 20. The gear 22 meshes 75 with the gear 23, while the gear 23 is in mesh with the gear 24. The gears 23 and 24 are secured to and adapted to operate the shafts 14 and 15, respectively.

The forming wheels 12 and 13 are removable or replacably held on the shafts 14 in an ordinary well known manner, the detail of which is not illustrated in the drawings, so that different forming wheels may be employed in the carrying out of my method. 80 Each of the wheels 12 and 13 are formed with an inner surface 25 which is of a design, decoration or shape so as to provide the desired shape and design to the outer surface of the came A adapted to be passed 85 through the machine B.

The machine B is provided with a pair of guide wheels 26 which are supported by the bifurcated brackets 27 in a manner so as to hold the wheels diametrically opposite 95 each other and to cause the surface of the wheels 26 to engage the shank 28 of the came A in a manner to squeeze the shank together and at the same time firmly grip the came on the shank while the came is 100 passing through the machine B. The width of the guide wheels 26 is such as to freely fit the glass recesses or channels 29 formed in the side of the came A, as illustrated in the diagrammatic illustration in Figure 4, 105 and as would be apparent from the front view in Figure 1. In fact, the guide wheels fit the recesses or channels 29 closely so that as the came A passes through the forming rollers 12 and 13 the material of the came 110 is squeezed closely against the wheels 26 and the serrated surface of the wheels 26

is caused to bite into the shank 28 to provide a serrated inner surface 30 to the shank 28 and at the same time squeezing the body of the came A firmly against the 5 steel rib 10 from all sides to form the came of the desired cross sectional shape and to impress into the surface thereof the decorative finish such as 32, illustrated in Figure 6. This decorative surface may be of the 10 same design and nature as the decorative surfaces 25 on the wheels 12 and 13, and thus I provide a method of making cames for leaded glass windows of a most desirable 15 nature, having a design adapted to be attractive and at the same time facilitate the better making of the came itself.

The plain unfinished design of the came is illustrated in Figure 5, while the finished 20 drawn out came which has been reworked with the desired outer design or finish is clearly illustrated in Figure 6. By changing 25 the wheels 12 and 13 to substitute wheels with a different surface design, I can make many different designs by passing the same through the forming machine B. Thus in carrying out my method the rough unfinished came which comes from the extrusion machine is adapted to be passed through the forming machine B wherein the desired 30 design or configuration is pressed and formed into the came body, stretching the came out as it passes through this forming process and at the same time providing a finished came much to be preferred over 35 the ordinarily extruded came.

My method consists in placing the extruded came in position to be engaged on 40 practically all sides thereof and then drawing the same out to form a finished came with a decorative or configured outer face and providing a finished came to the desired size and nature with an outer decorative face. The method is simple yet very effec-

tive in providing a finished came with practically little or no extra costs in the formation of the same as it is necessary to form the came about the reinforcing rib 10 in this construction and even without the rib 10 it is necessary that the came be formed of the desired size and shape so that in passing 45 the came into the decorative forming rollers 12 and 13 I provide a method of making and forming the same which is very desirable. My method has been successfully carried out in making cames with a ham- 50 mered design, a rough cast design having a very roughened outer surface, a frosted design and many other attractive designs to the outer surface and formation 55 of the came.

In accordance with the patent statutes I have described the principles of operation of my method and while I have illustrated means of carrying out the method, I desire to have it understood that this is only suggestive and that the method can be carried 60 out by other means and applied to uses other than those herein set forth and I desire to have it understood that I wish to protect the invention within the scope illustrated 65 and as set forth in the following claim.

I claim:

The method of finishing and ornamenting lead came of the type consisting of two substantially parallel flanges joined at substantially their central portions by a web comprising passing the came through rotary die means acting upon the outer surfaces of said flanges to ornament the same and at the same time passing the web of the came 70 through rotary means disposed at right angles to said die means to serrate both surfaces of said web and force the material of said web about a reinforcing means therein.

WILLIAM J. BURROWS.
